The ornamental design for a mini projector system, as shown and described.

DESCRIPTION

FIG. 1 is a top perspective view of our design for a mini projector system;

FIG. 2 is a bottom perspective view of our design for a mini projector system;

FIG. 3 is a front elevational view of our design for a mini projector system;

FIG. 4 is a rear elevational view of our design for a mini projector system;

FIG. 5 is a right side view of our design for a mini projector system;

FIG. 6 is a left side view of our design for a mini projector system;

FIG. 7 is a top view of our design for a mini projector system;

FIG. 8 is a bottom view of our design for a mini projector system;

FIG. 9 is a top perspective view of our design for a mini projector;

FIG. 10 is a bottom perspective view of our design for a mini projector;

FIG. 11 is a front elevational view of our design for a mini projector;

FIG. 12 is a rear elevational view of our design for a mini projector;

FIG. 13 is a right side view of our design for a mini projector;

FIG. 14 is a left side view of our design for a mini projector;

FIG. 15 is a top view of our design for a mini projector;

FIG. 16 is a bottom view of our design for a mini projector;

FIG. 17 is a top perspective view of our design for a mini projector system with a panel of the mini projector in a raised position;

FIG. 18 is a bottom perspective view of our design for a mini projector system with a panel of the mini projector in a raised position;

FIG. 19 is a front elevational view of our design for a mini projector system with a panel of the mini projector in a raised position;

FIG. 20 is a rear elevational view of our design for a mini projector system with a panel of the mini projector in a raised position;

FIG. 21 is a right side view of our design for a mini projector system with a panel of the mini projector in a raised position;

FIG. 22 is a left side view of our design for a mini projector system with a panel of the mini projector in a raised position;

(Continued)

FIG. 23 is a top view of our design for a mini projector system with a panel of the mini projector in a raised position; and,

FIG. 24 is a bottom view of our design for a mini projector system with a panel of the mini projector in a raised position. The broken lines in the drawings depict portions of the mini projector system and form no part of the claimed design.
